UNITED STATES PATENT OFFICE.

EMIL S. ANDERSON, OF CHICAGO, ILLINOIS.

CURTAIN STRETCHER.

Application filed August 2, 1921. Serial No. 429,216.

To all whom it may concern:

Be it known that EMIL S. ANDERSON, a citizen of the United States of America, residing at Chicago, in the county of Cook 5 and State of Illinois, has invented new and useful Improvements in Curtain Stretchers, of which the following is a specification.

The object of the invention is to provide a simple and efficient construction of 10 stretcher for lace curtains and the like and particularly to provide a connection between the main longitudinal and transverse frame elements whereby the proper angular relation of said parts may be maintained 15 while permitting of the necessary adjustment to accommodate curtains of different dimensions; and with these objects in view the invention consists in a construction and combination of parts of which a preferred 20 embodiment is shown in the accompanying drawings, wherein:—

Figure 1 is a plan view of a stretcher embodying the invention.

Figure 2 is a transverse sectional view 25 of the same on the plane indicated by the line 2—2 of Figure 1.

Figure 3 is a detail view of one of the coupling members detached.

Figure 4 is a detail transverse section of 30 one of the stretcher bars on the plane indicated by the line 4—4 of Figure 1 to show the construction and mounting of curtain engaging pins.

Figure 5 is a detail view of one of the 35 pins.

The stretcher consists of the longitudinal 40 stretcher bars 10 which may be graduated as indicated and a transverse connecting bar 11, and connecting the longitudinal 45 stretcher bars are transverse stretcher bars 12 which also may be graduated as illustrated in common with the intermediate connecting bar 11.

The connection between the intermediate 50 bar 11 and the longitudinal stretcher bars consists of couplers 13 made preferably of heavy sheet metal of which the head portions 14 are transversely T-shaped and the shank portions 15 transversely U-shaped, 55 as indicated clearly in Figure 3. The shank portions of the couplers embrace and engage the bar 11 while the head portions are secured to the under faces of the longitudinal stretcher bars by means of rivets 18, these rivets also passing through and se-

curing to the longitudinal stretcher bars the plates 17 secured to the outer faces thereof. The upper of the T-couplings having its shank secured to the bar 11 by means of a rivet 19 while the lower coupling is 60 secured to the bar by means of a bolt 20 engaging a longitudinal slot 21 in the cross bar to provide for relative lateral adjustment of the lower longitudinal stretcher bar at an intermediate point to correspond with 65 the adjustment made with reference to the transverse bars 12.

The terminals of the longitudinal stretcher bars are connected with the transverse stretcher bars by similar bolts 22 passing 70 through longitudinal slots 23 in the longitudinal stretcher bars and through the transverse stretcher bars, two of said bolts extending through slots 24 in the transverse 75 stretcher bars of which each is provided with a slot at the end corresponding with the slot 21 in the intermediate or transverse frame bar 11. These bolts are provided with suitable thumb nuts for locking the bars in their adjusted positions. 80

At their inner edges the longitudinal and transverse stretcher bars are reduced in thickness to form ledges 25 and carried by these ledges are the curtain engaging 85 pins 26 which in the construction illustrated are of double form having intermediate slide portions 27 fitted in the oppositely extending guide kerfs 28 formed in the bars and extended at their ends to form the hooks 29 which project into the angles 90 formed by the ledges 25 to engage the edges of the curtain or object to be stretched. The pins are adapted to be adjusted in the kerfs while displacement thereof is prevented by the oppositely facing relation of 95 said kerfs and the engagement of opposite sides of the body portions of the pins therewith.

Having described the invention, what is 100 claimed as new and useful is:—

A curtain stretcher having longitudinal 105 stretcher bars and transverse stretcher bars adjustably connected with the longitudinal stretcher bars, a transverse frame bar spanning the longitudinal stretcher bars at intermediate points, T-couplings connecting the transverse frame bar with the longitudinal stretcher bar and embodying U-shaped shanks and transversely T-shaped heads of which the latter are secured 110

to the under face of the longitudinal stretcher bar and the former disposed in embracing relation to the transverse frame bar, plates secured on the outer faces of the 5 longitudinal stretcher bars at intermediate points, and rivets passing through said plates, through the longitudinal stretcher bars and through the heads of the T-cou-

plings, the shank of one of said T-couplings being permanently secured to the transverse 10 frame bar and the shank of the other T-coupling adjustably secured to said transverse frame bar.

In testimony whereof he affixes his signature.

EMIL S. ANDERSON.
